BOWLING LANE PINSPOTTTER MASK

Thomas A. Meade, Huntington, N.Y., assignor to AMF Incorporated, White Plains, N.Y.

Filed Jan. 24, 1974, Ser. No. 436,057

Term of patent 14 years

Int. Cl. D21—02

U.S. Cl. D34—5 DD

FIG. 1

FIG. 2

FIG. 3

FIG. 4

FIG. 1 is a perspective view of a bowling lane pinspotter mask of my design;

FIG. 2 is a front view;

FIG. 3 is a top plan view; and

FIG. 4 is a sectional view taken along the line 4—4 in FIG. 2.

I claim:

The ornamental design for a bowling lane pinspotter mask, as shown and described.
